(57) **CLAIM**

The ornamental design for a long handle grill brush as shown and described.

DESCRIPTION

FIG. 1 is a top, front, right side isometric perspective view of a long handle grill brush in accordance with our design; FIG. 2 is a bottom, rear, right side isometric perspective view of the long handle grill brush of FIG. 1;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines shown in the drawings represent portions of the long handle grill brush that form no part of the claimed design.
